UNITED STATES PATENT OFFICE

93,346

DESIGN FOR A SHOE

Nicholas J. Grossman, Lynn, Mass.

Application July 13, 1934, Serial No. 52,573

Term of patent 3½ years

To all whom it may concern:

Be it known that I, NICHOLAS J. GROSSMAN, a citizen of the United States, residing at Lynn, in the county of Essex and State of Massachusetts, have invented a new, original, and ornamental Design for a Shoe, of which the following is a specification, reference being had to the accompanying drawing, forming a part thereof, in which

The figure is a view in perspective of a shoe showing my new design, a conventional heel and sole being indicated therein in dot and dash lines.

I claim:

The ornamental design for a shoe substantially as shown and described.

In testimony whereof, I have affixed my signature hereto.

N. J. GROSSMAN.
